UNITED STATES PATENT OFFICE.

FREDERICK GARDNER COTTRELL, OF BERKELEY, CALIFORNIA, ASSIGNOR TO INTERNATIONAL PRECIPITATION COMPANY, OF LOS ANGELES, CALIFORNIA, A CORPORATION OF CALIFORNIA.

METHOD OF DISCHARGE OF ELECTRICITY INTO GASES.

1,067,974.

Specification of Letters Patent. Patented July 22, 1913.

Application filed November 6, 1911. Serial No. 658,657.

To all whom it may concern:

Be it known that I, FREDERICK GARDNER COTTRELL, a citizen of the United States, residing at Berkeley, in the county of Alameda and State of California, have invented new and useful Improvements in the Method of Discharge of Electricity Into Gases, of which the following is a specification.

10 My invention relates in general to facilitating the discharge of electricity from solid conductors into gases and more particularly for the purpose of causing the deposition of suspended matter as for instance is described at length in my U. S. Patent No. 895,729, August 11th, 1908.

Various procedures and apparatus proposed for the electric deposition of suspended matter from gases have involved 20 the use of "collecting electrodes" of one constant polarity having a smooth and usually relatively large surface placed in juxtaposition to "discharge electrodes" of the opposite polarity usually of smaller surface, as for example, a single wire or a conductor provided with sharp points, edges, or fine fibers or scales (all of which will hereafter be generically referred to as "discharge electrodes") from which electrical discharge more easily takes place.

One of the simplest possible arrangements of this kind is represented in the accompanying drawing, which is a diagrammatic vertical section of an apparatus suitable for carrying out the process.

In this apparatus (1) is a metallic cylinder serving simultaneously to hold the gas being subjected to discharge and as smooth positive or collecting electrode. The negative discharge electrode (2) is represented as provided with discharge points by a wrapping (3) of fibrous asbestos twine. This electrode is insulated from the vessel (1) by the non-conducting stopper (4).

45 Any suitable source of high potential electricity is conventionally indicated by (5). Gas may be passed through the vessel by means of the inlet (6) and the outlet (7). A number of such units may be operated in parallel or a plurality of electrodes of both types may be variously grouped in common chambers.

Throughout the patent specifications and other literature on this subject, as far as any

choice of actual polarity is in anyway indicated, it appears to be the positive conductor from the source of electricity which has been connected to the "discharge electrode" *e. g.* U. S. Pats. Walker, No. 342,548; Thwaite, No. 617,618. As the gases and suspended matter between the electrodes are constantly receiving electricity from the "discharge electrodes" and as quickly giving it up to the collecting electrodes it is perhaps natural that our recognized convention, whereby electricity is treated as flowing from the positive conductor to the negative, should have led to the assumption that the discharge electrode should be made the positive.

In the early laboratory experiments leading up to the process covered by the patent above cited, it was soon recognized that the same general effect of deposition of suspended matter upon the collecting electrodes was accomplished whether these were made the positive or negative so long as the discharge electrode had the opposite sign and these polarities were not too rapidly reversed, *i. e.* as long as the current flowing was "essentially direct". With the apparatus then at command neither direction of the current was noticed to present any clearly marked advantages over the other. This same conclusion is positively stated by Prof. Oliver Lodge in an article in *Journal Society Chemical Industry*, 5—572—576 (1886), which has been the incentive and starting point for most of the practical work in this line including that of the present applicant.

It seems probably true that about the same precipitation of dust is effected by an equal quantity of either positive or negative electricity discharged through a given apparatus under the same difference of potential, all other conditions being the same. In operating on a small scale, as in the laboratory, the difference in the ease of control of the discharge from the positive and negative discharge electrodes is a factor of such minor importance that it was at first overlooked. It was not until installations were undertaken on a larger scale that it was discovered to be of great practical importance to connect the negative conductor to the discharge electrode and the positive conductor to the collecting electrode. The chief ad-

vantage in this choice of polarity over that indicated in previous specifications above referred to appears to be that with it a higher potential difference and greater flow 5 of electricity may be maintained between the opposite electrodes without the discharge passing from the "silent" form to the "disruptive," *i. e.* sparks or arcs, and in consequence a much swifter current of gas can be 10 treated in the same apparatus. One reason for this important relationship having so long escaped recognition probably lies in the fact that few of the investigators in this 15 field have ever reached a really large scale and the laboratory apparatus, such as static electric machines, induction coils and the like, have had little tendency to crowd the electrodes and precipitation chambers to their 20 fullest attainable capacity where the conditions above described assume their full significance.

My invention is based on the discovery that by causing the discharge to pass wholly or mainly from the negative electrode instead of from the positive electrode, the potential difference may be increased without disrupting the dielectric and in carrying out the invention I therefore apply the negative potential to the electrode which by reason of its pubescent, pointed, or other special character, is adapted to promote the "silent discharge" and the potential difference I apply to the electrodes is in excess of that which can be maintained between the electrodes when the positive potential is applied 35 to the discharging electrodes, other conditions remaining the same.

Having thus described my invention, what

I claim as new and desire to secure by Letters Patent is:—

1. The method of maintaining nondisruptive discharge, at maximum potential, through gases, which consists in applying a difference of potential to electrode surfaces exposed to the gas, such surfaces being of different character so as to favor discharge in a given direction through the gas, the negative potential being applied at the surface from which the discharge passes and the potential difference being in excess of that which can be maintained when the positive potential is applied to said surface.

2. The method of maintaining a nondisruptive discharge at maximum potential through gases, which consists in exposing to the gas a surface facilitating a non-disruptive discharge, and applying to such surface a negative potential, approximating the disrupting potential.

3. The method of separating suspended particles from gases, which consists in subjecting the gas to the action of a discharging electrode, and maintaining said electrode at a negative potential which is approximately the maximum that can be obtained without disruption of the gas, and is in excess of the positive potential that could be maintained, under the same conditions, without disruption.

In witness that I claim the foregoing I have hereunto subscribed my name this 31st day of October 1911.

FREDERICK GARDNER COTTERELL.
